UNITED STATES PATENT OFFICE.

LYNN D. RUDOLPH, OF CHICAGO, ILLINOIS.

VACUUM-CLEANER NOZZLE.

1,278,222.

Specification of Letters Patent. Patented Sept. 10, 1918.

Application filed September 30, 1916. Serial No. 123,019.

To all whom it may concern:

Be it known that I, LYNN D. RUDOLPH, a citizen of the United States of America, and a resident of Chicago, county of Cook, and 5 State of Illinois, have invented certain new and useful Improvements in Vacuum-Cleaner Nozzles, of which the following is a specification.

This invention relates to improvements 10 in vacuum cleaner tools, particularly such as are used to clean floors.

The main objects of this invention are to provide an improved means for a tool or nozzle of this kind which will cause the tool 15 to pick up small articles such as matches, cigar stubs, scraps of paper, hair and other surface dirt, more readily than other devices heretofore in use; and to provide a nozzle of this kind having improved means 20 for adjusting the mouth thereof to adapt the device to the usual other purposes for which vacuum cleaners are used.

In the accompanying drawings Figure 1 is a front elevation of an illustrative embodiment of this invention.

Fig. 2 is a bottom view of the same.

Fig. 3 is a cross section of the same taken on the line A—A of Fig. 1.

Fig. 4 is a front elevation of another form 80 of the tool wherein the mouth is adjustable.

Fig. 5 is a cross section of the same taken on the line B—B of Fig. 4.

Fig. 6 is a fragmentary cross section of 85 the same but showing the flexible lip of the nozzle in its raised position.

Fig. 7 is a detail of the means for adjusting the lip of the nozzle.

Many vacuum cleaner nozzles are provided 90 with mouths so formed as to contact more or less with the surface operated upon, around the entire outer edge of the mouth, for the purpose of limiting the open area through which a current of air may flow in order that the maximum velocity of such 95 current may be obtained. Accordingly when such nozzles are reciprocated over a floor and engage comparatively large articles, such as cigar stubs, they may fail to lift the same into the dust receptacle, these articles being 100 merely rolled along in front of the nozzle.

Such articles ordinarily cannot be drawn 105 into the vacuum cleaner by tilting the nozzle, since the velocity of the current of air is thereby greatly reduced, due to the excessively wide area of the exposed open mouth of the nozzle in such case.

The purpose of the present invention is to provide a construction of cleaner nozzles which will permit comparatively large articles to pass into the nozzle while the necessary flow of air to lift such articles may be maintained.

In the construction shown in the drawings, the cleaner nozzle 1 comprises a flared tubular body 2 having an oblong mouth and arranged for connection to the usual vacuum cleaner apparatus. The inner wall or lining 8 of the nozzle may be made of rubber, or some other flexible material, or it may be made of rigid material, provided a suitable 60 arrangement is included for permitting comparatively large articles to pass into the tube through one of the walls thereof rather than directly through the usual mouth opening at the bottom of the tube.

For the usual purpose of disengaging dust from surfaces operated upon a brush 1 partially surrounds the inner wall 8 of the tube and is provided with a layer of bristles 6 which extend downward to or slightly beyond the lowest extremity of the cleaner to operatively contact with the surface to be cleaned. The bristles surround the inner tube on three sides but have a gap as at 7. When matches, cigar stubs or other small articles are to be drawn into the tube, the cleaner approaches the article at the side where the gap occurs, and such article is 75 not brushed aside by the bristles.

Means to facilitate drawing the articles 80 into the tube may be permanent as shown in Fig. 1, or adjustable as shown in Fig. 4.

In Fig. 1, the tube is shown formed with a recess in its front edge to provide a gap 85 between the tube and the floor upon which the tube is adapted to be placed. This gap may also be provided for by rolling part of the flexible tube back as shown in Fig. 6. This gap is adjacent to the gap in the layer of bristles, so that when the cleaner 100 approaches a comparatively large article, the gap in the bristles permits the cleaner to pass partially over the articles. The suction at the gap 9 draws the article into the tube or permits the front wall of the tube 105 to pass over it, whence it is sucked upward with the rest of the dirt.

The inner wall of the curtain is preferably provided with a reinforced edge 10 which may be of coiled wire as shown in Fig. 4.

The tool is secured to the body 2 by means 110 of screws 3. Close contact therewith is

facilitated by a layer of felt 4 which is placed intermediate the upper tube and the brush.

Adjustable means for permitting and facilitating the entrance into the tube of larger articles such as matches and the like, are shown in Fig. 4. In the construction shown in this figure, the inner lining is adapted to contact at its lower extremity with the surface to be cleaned. When it is desired to pick up a small article, the tool is pushed forward so that the gap in the bristles will permit the article to enter the inclosure. The operator may then shift a manually controlled slide 17 upwardly, and since the lower end of the slide or rod 17 is connected to the outer edge of the inner lining 8, a portion of the lining is lifted upwardly, providing a gap 9 as shown in dotted lines in Fig. 4. The rod 17 is retained in its upper position by means of an annular coiled spring 16 surrounding the rod 17 and seated in a recess 15 in the body portion 1. The spring is retained in recess 15 by a flange 18 of part 2 of the cleaner. The rod 17 is provided with a double cone portion 19 for coöperating with the spring in such manner that the spring will cause the rod 17 to be shifted to its extreme positions after the rod is manually shifted to cause the cone to pass the center of the annular spring.

Although but two specific embodiments of this invention are herein shown and described, it will be understood that numerous details of the construction shown may be altered or omitted without departing from the spirit of this invention as defined by the following claims.

40 I claim:

1. A vacuum cleaner nozzle, comprising a supporting member, a tube of oblong cross section depending therefrom and adapted to contact with the surface to be cleaned, said tube having a recess formed along one edge of its lower end and above said surface to permit articles to be more readily admitted to the space within said tube, and a row of brush bristles adjacent to said tube and arranged to contact with the surface to be cleaned.

2. A vacuum cleaner nozzle, comprising a supporting member, a tube of oblong cross

section depending therefrom and adapted to contact with the surface to be cleaned, 55 said tube adapted to have a recess formed along one edge of its lower end and above said surface to permit articles to be more readily admitted to the space within said tube, and means for adjusting said tube to 60 form said recess.

3. In a cleaner, a nozzle member having a flexible mouth arranged to have one portion of its edge raised to form a recess therein and with respect to the surface to be 65 cleaned to form a gap above said surface, and means for adjusting said mouth to open or close a gap therein above the surface being cleaned.

4. In a cleaning device, a mouth tube of 70 flexible material having an edge adapted to contact with the surface to be cleaned and having a portion of said edge adapted to rest above said surface to form a recess therein, means for raising said edge portion 75 of the tube from said surface, and a brush outside the tube having a gap adjacent said portion of the tube.

5. In a cleaning device, a flexible mouth tube provided at its lower extremity with 80 a coiled wire reinforcement adapted to strengthen but not destroy the flexibility of said tube, means for flexing said mouth tube to provide a gap at one side, and a brush having bristles adapted to operatively 85 engage the surface to be cleaned, partially surrounding said tube.

6. In a cleaner, a nozzle member having a flexible mouth arranged to have one portion of its edge raised and lowered with respect to the surface to be cleaned to form a gap above said surface, means for adjusting said mouth to open or close a gap therein above the surface being cleaned, said 90 means comprising a bar movably mounted in the nozzle member and secured to the flexible mouth thereof and having a double cone portion, and an annular coiled spring seated in said nozzle member and surrounding said bar for the purpose of co-operating with the double cone portion thereof.

Signed at Chicago this 26th day of Sept. 1916.

LYNN D. RUDOLPH.
